ATTORNEY

UNITED STATES PATENT OFFICE.

ROBERT SMITH, OF NEAR SAN JOSE, CALIFORNIA.

STRIKER PLATE.

Application filed October 2, 1924. Serial No. 741,252.

To all whom it may concern:

Be it known that I, ROBERT SMITH, a citizen of the United States, and residing near San Jose, in the county of Santa Clara 5 and State of California, have invented certain new and useful Improvements in Striker Plates, of which the following is a specification.

In the building of automobile bodies and 10 in architectural work where hinged doors are used, a striker plate is mounted upon the door jamb and so adjusted that when the door is swung shut the latch will engage the opening therein and hold both the door 15 and latch in a closed position without rattling. After the lapse of a little time, especially in the case of automobiles, constant use will so loosen the door that the latch will move somewhat in the keeper causing 20 an unpleasant rattling.

It is the object of the present invention to provide a striker plate or keeper so constructed as to be readily adjusted from time to time to positively secure the door against 25 rattling.

In the drawing:—

Figure 1 is a face view of a striker plate embodying my invention.

Figure 2 is a sectional view on line 2—2 30 of Figure 1.

Figure 3 is a perspective view of the adjustable member of the striker plate.

Referring more particularly to the drawing, I show at 1 a portion of a door jamb 35 recessed at 2 to receive the bar 3 of the latch on the door mounted therein.

At 4 I show a striker plate having an opening 5 formed therein and held in position on the door jamb by means of screws 6, 40 its inner portion being turned at right angles to close off the recess 2 from the interior of the car as shown at 7.

This is ordinary construction except as to part 7, and when the door is closed the bar 3 45 engages edge 8 of opening 5 and it is the play of the bar 3 against this edge when the door is closed that causes annoyance.

To overcome this condition I provide a plate 9 having an opening 10 formed there-

in, preferably of the same size and form as 50 the opening in striker plate 4 and normally aligning therewith.

This plate 9 is also provided with slots 11, each slot engaging a screw 6 and lying parallel to the opening in striker plate 4 in 55 the direction of movement of latch bar 3 when the door is opened or closed.

Turned inwardly from the front edge 12 of plate 9 is a flange 13, and extending inwardly from the opposite edge 14 is a flange 60 15. The flange 15 is tapped at 16 and the portion 7 of plate 4 is drilled at 17 to receive a screw 18.

When the device is assembled as shown 65 the plate 9 lies flat against the inner surface of striker plate 4 and it is obvious that by turning screw 18 with its head bearing against portion 7 of plate 4 the whole plate 9 is drawn inwardly.

Assuming that the device has been in use 70 some time and it has become necessary to take up the play of bar 3 in opening 5, the screws 6 are loosened, and the screw 18 turned until the plate 9 is moved inwardly the desired distance and the screws 6 again 75 tightened. The latch bar 3 now engages edge 12 of plate 9 instead of engaging edge 8 of plate 4 and no movement of the door is permitted.

It is obvious, of course, that many changes 80 in form, construction, and method of operation may be made without departing from the spirit of the invention, and it is to be understood, therefore, that it is desired to cover the invention broadly within the scope 85 of the appended claim.

It is clear from the foregoing disclosure 90 that I have provided a device that is simple in form and construction, economical to manufacture, and highly efficient in its practical application.

I claim:—

A striker plate consisting of a plate having an opening receiving opening formed therein and an end portion formed at right angles to the plane of said opening, said end portion having an orifice formed therein, and means 95 for securing said plate to a door jamb, a

second plate slidably mounted against the inner side of said first plate and having its central portion cut and bent back to form two parallel flanges and to form a latch receiving opening therein and having slots therein to receive said securing means, one of said flanges normally being in alignment

with one edge of said latch receiving opening, and the other flange being threaded to receive a screw, and a screw slidably engaging the orifice in the first mentioned plate and threaded into the last mentioned flange on the second mentioned plate. 10

ROBERT SMITH.
